B. LIBERMAN

CIGAR BUNCHING

Filed Nov. 16, 1921

UNITED STATES PATENT OFFICE.

BERNARD LIBERMAN, OF PHILADELPHIA, PENNSYLVANIA.

CIGAR BUNCHING.

Application filed November 16, 1921. Serial No. 515,446.

To all whom it may concern:

Be it known that I, BERNARD LIBERMAN, a citizen of the United States, residing at Philadelphia, in the county of Philadelphia, State of Pennsylvania, have invented a new and useful method and means for Cigar Bunching, of which the following is a specification:

My invention relates to cigar bunching; 10 The object is to provide improved method and means whereby a measured charge of tobacco is received from the supply, separated from said supply and delivered to the bunching table in such a way that the 15 charge shall have an approximately even density throughout. To this end the invention comprises method and means for pushing the charge evenly into the measuring pocket and preventing a portion of the 20 charge from being packed or unduly compressed at one side of the pocket.

The invention is an improvement on the method and means described and claimed in the pending application filed by Bernard 25 Liberman on Nov. 24, 1920, having Serial No. 426,184. In that device the measuring pocket was provided, along one longitudinal margin thereof, with a severing knife, which was adapted to cooperate with means 30 forming a cutting edge arranged adjacent to one margin of the hopper opening which discharged to said measuring device. In the operation of such a device it was found that, as the measuring device rotated relatively as to the hopper opening, the tobacco lying in the top of the measuring pocket was pushed or scraped toward the side of the pocket containing the knife. This resulted in carrying away some of the tobacco 35 that should normally lie in the pocket near the opposite margin, and in unduly compressing and packing the tobacco toward the side of the pocket having said knife. The result was an uneven distribution of 40 the tobacco in the pocket and consequently an irregular and uneven charge for the bunch. I have overcome this objection by the following method, and the means for effecting the same, herein described.

45 Referring to the drawings, which illustrate merely by way of example, suitable means for effecting my invention:—

Fig. 1 is a vertical section of the part of a bunching machine showing my invention.

Fig. 2 is a fragmentary section showing parts in different position. 55

Fig. 3 is an elevation of same after the measuring device has made a little more than a quarter turn from the position shown in Fig. 1. 60

Fig. 4 is a section on line 4—4 of Fig. 3.

Fig. 5 is a perspective view, on an enlarged scale, of the element comprising my improvement. 65

Similar numerals refer to similar parts throughout the several views.

The lower portion of the hopper, indicated at 6, is adapted to discharge to the measuring device which comprises the rotating element 7 seated in the arc-shaped flanges 8 of the hopper 6 and provided with the pocket 9. The depth of the pocket is adjusted by the member 10, operated by the screw 11, having the knurled head 12. One margin of this pocket 9 is provided with means forming the knife edge 13. This margin, and consequently the knife edge 13, is inclined to the plane passing through the axis of the rotating element 7. It will be understood that three of the margins or sides of the opening in the bottom of hopper 6 correspond approximately with three margins of the pocket 9; the other side of the hopper however is recessed as at 14 and is provided with a plate 15 recessed as at 16. This recess 16 registers approximately with the end margins of pocket 9. Over the plate 15 is clamped the recessed element 17 having a curved and inclined formation or wall, as at 18, extending to the periphery of element 7, as at 19, and provided at this point with the knife 20 having its edge adapted to cooperate with the edge of knife 13, as in Fig. 2. The curved wall 18 is provided with the flanking walls 21 which engage the rotating element 7 approximately at each end of the pocket 9. 70

As shown in Figs. 1 and 2 the rotating element 7 is adapted to rotate in the counter-clockwise direction from the position, as in Fig. 1, in which it receives the charge from the hopper 6, to the position as in Fig. 4, to discharge to the trough 22, which in turn delivers to the funnel or other means for carrying the charge to the bunching apron, 75 not shown. 80

In operation:

When the rotating element 7 is in the po-

sition shown in Fig. 1, its pocket 9 is filled with scrap tobacco from the supply contained in the hopper 6. As the element 7 then rotates in the direction of the arrow 5 shown in Fig. 1, the tobacco which is stationary in the hopper tends to separate from the tobacco which is contained in the pocket 9, and, as the hopper approaches the position shown in Fig. 2, whatever tobacco is 10 carried by the pocket away from the main supply contained in the hopper, is brought into the recess formed between the rotating element 7 and the inclined wall 18. As the element 7 continues to rotate, the knife 15 edge 13 approaches, and finally reaches the knife edge 20, so that the major portion of the tobacco that lies between the top margin of the pocket and the inclined wall 18 is pressed into a normal plane correspond- 20 ing with the top of the pocket before the knives 13 and 20 cooperate to completely sever the contents of the pocket from the supply. In other words nearly all of the tobacco which is carried from the main body 25 contained in the hopper, and which would tend to be scraped from the top of the pocket, or project above the plane of its top margin will be gently and evenly pressed by the inclined and nearly tangential wall, 30 before the edges 13 and 20 come together with a shearing action.

What I claim is:—

1. In the art of bunching, the method of separating measured charges of scrap tobacco from a supply, which consists in pressing evenly into a normal plane, the exposed surface of the measured charge which projects above said normal plane, and then severing the body of the charge from the supply.

2. In a scrap bunching machine, the combination of an element provided with a measuring pocket, movable to and from the receiving position and the discharge position, means for delivering scrap to said pocket, means connected therewith forming an inclined wall extending toward the margin of the pocket as it approaches the discharge position for gradually and progressively pressing evenly into a normal plane a projecting portion of the charge, and cooperating knives associated with the margin of the pocket and the margin of said inclined wall respectively for severing portions of scrap projecting above said normal plane.

3. Means for delivering measured charges of scrap tobacco for cigar bunching, comprising a rotating element having a measuring pocket, a hopper delivering thereto, means associated with said hopper forming a curved surface adjacent the delivery opening of the hopper and in the line of travel of the pocket and approximately tangential to the periphery of the rotating element, as

means for evenly pressing the filler into the pocket as the same moves away from the body of filler in the hopper, and means forming cooperating knives for severing the measured charge from the supply.

4. Means for delivering measured charges of scrap tobacco for cigar bunching, comprising a rotating element having a measuring pocket provided with a cutting edge at its rear margin, a hopper delivering thereto, means associated with said hopper forming a recess with a curved surface, adjacent the delivery mouth of the hopper approximately tangential to the periphery of the rotating element, and provided with means forming a cooperating cutting edge adjacent the periphery of rotating element.

5. Means for delivering measured charges of scrap tobacco for cigar bunching, comprising a rotating element having a measuring pocket provided with a cutting edge at its rear margin, a hopper delivering thereto, means associated with said hopper forming a recess with a curved surface, adjacent the delivery mouth of the hopper approximately tangential to the periphery of the rotating element, and provided with means forming a cooperating cutting edge adjacent the periphery of rotating element, said cooperating cutting elements inclined to each other to give a shearing action.

6. Means for delivering measured charges of scrap tobacco for cigar bunching, comprising a rotating element having a measuring pocket provided with a cutting edge at its rear margin, a hopper delivering thereto, means associated with said hopper forming a recess with a curved surface, adjacent the delivery mouth of the hopper approximately tangential to the periphery of the rotating element, and provided with means forming a cooperating cutting edge adjacent the periphery of rotating element, said cutting elements cooperating to sever portions of scrap projecting from the pocket.

7. In a scrap bunching machine, the combination of means forming a measuring pocket, movable to and from receiving and discharging positions, a hopper for delivering scrap thereto, means forming an offset recess at the hopper base having a wall converging toward the pocket providing means whereby the scrap in the offset recess is pressed into the pocket as the pocket moves toward the discharging position, and cooperating knives arranged and operated to shear off all tobacco projecting from the pocket as the pocket passes beyond the offset recess.

8. In a scrap bunching machine, the combination of means forming a measuring pocket, movable to and from receiving and discharging positions, a hopper for delivering scrap thereto, means forming an offset

- recess at the hopper base having a wall converging toward the pocket providing means whereby the scrap in the offset recess is pressed into the pocket as the pocket moves toward the discharging position, a knife on the margin of the offset recess and a knife forming a margin of the pocket adapted to cooperate to cut off scrap projecting from the pocket.
9. In a scrap bunching machine, the combination of means forming a measuring pocket, movable to and from receiving and discharging positions, a hopper for delivering scrap thereto, means forming an offset recess at the hopper base having a wall converging toward the pocket providing means whereby the scrap in the offset recess is pressed into the pocket as the pocket moves toward the discharging position, a knife on the margin of the offset recess and a knife forming a margin of the pocket adapted to cooperate with a shearing action to cut off scrap projecting from the pocket.

BERNARD LIBERMAN.
